UNITED STATES PATENT OFFICE.

HERMANN OP DE HIPT, OF OEFLINGEN, GERMANY, ASSIGNOR TO THE FIRM OF I. WECK. GESELLSCHAFT MIT BESCHRÄNKTER HAFTUNG, OF OEFLINGEN, GERMANY.

STERILIZING APPARATUS.

1,021,946.

Specification of Letters Patent.

Patented Apr. 2, 1912.

Application filed January 19, 1909. Serial No. 473,137.

To all whom it may concern:

Be it known that I, HERMANN OP DE HIPT, a subject of the German Emperor, and a resident of Oeflingen, Grand Duchy 5 of Baden, Germany, have invented certain new and useful Improvements in Sterilizing Apparatus, of which the following is a specification.

This invention relates to improvements in 10 sterilizing apparatus in which the sterilizing cans are closed by means of springs engaging the lids of the cans. And the object of the improvements is to provide an apparatus, which is simple in construction 15 and enables cans of different heights to be placed thereon and closed by the springs. With this object in view, the lid closing springs can be adjusted to different distances from the base plate or plates supporting the cans.

To illustrate the invention, several examples thereof have been described herein-after, reference being had to the accompanying drawings forming a part of this 25 specification.

In said drawings, Figure 1, is a side view of the apparatus partly in section; Fig. 2, is a horizontal cross-section of Fig. 1 taken on the line A, Fig. 3, is a detail view showing a spring for holding the lid in closed position, Fig. 4, is a side view similar to that of Fig. 1, to illustrate a modification of the apparatus, Fig. 5, is a horizontal cross-section of Fig. 4 taken on the line B, Figs. 30 6 to 8, are detail views showing modifications of the springs for holding the lids in closed position, and Fig. 9, is a perspective view of one of the adjustable base plates.

On a horizontal base plate 1 a hollow pillar 2 is supported, which is provided with 40 longitudinal slots 3. In the slots 3 springs for holding the lids 7 of the cans 8 in closed position can be adjusted to different distances from the base plate 1 according to 45 the height of the can placed on the latter.

The construction of the springs appears 50 from Figs. 1 to 4. As shown in those figures, a leaf spring 4 is bent upward at one of its ends to form a shank 5. To the same end a flanged piece 6 is secured having its flange directed downward and arranged at a certain distance from the shank 5. If it is desired to secure the spring to the pillar 2, the flanged piece 6 is inserted into one 55 of the slots 3, as appears from Fig. 2. In

the preferred construction the height of the flange of the piece 6 is equal to or slightly less than the breadth of the slots 3. As shown in Fig. 2, the spring is turned sideways while being inserted, whereupon it is turned at an angle of 90°, so as to assume its normal position. In the regular position of the spring, its shank 5 bears against the outside of the pillar, while the flange of the piece 6 bears against the inner side of the same. As shown in Fig. 1, both shanks are broader than the slots 3. If now the springs 4 are pushed downward and on the lids 7 of the cans 8, they are clamped on the pillar by means of the projecting shank 5 and the flange of the piece 6, and they exert a pressure on the lids which is so much the stronger the more the springs have been pressed downward and on the lids. In some cases it may be desirable to permit the 75 springs 4 to be turned sideways and out of the radial position relatively to the pillar 2. For this purpose, the springs 4 are pivotally connected to the flanged pieces 6, so as to swing in a horizontal plane when applied to 80 the pillar. This may be done by means of a pivot bolt 9 connecting the spring 4 and the piece 6. To permit the spring 4 to be freely turned about its pivot, its shank 5 is rounded as shown in Fig. 2. When using 85 springs which can be turned in the manner described, the can closing pressure of the springs can be applied to any point of the circle inclosed by the springs.

In the modification illustrated in Fig. 6, 90 the spring 4^a consists of a strong wire the shank of which extends through a T-shaped eye 19. The latter may also be made of wire, and the projecting shank of the spring is enlarged in a suitable way as shown at 20. 95 The eye 19 of the spring is inserted into the slot of the pillar in the same way as before described, so that the lateral projections of the eye bear against the inner surface of the pillar, while the enlarged portion 20 thereof bears against the outer side. Preferably the lateral shanks of the eye 19 are bent downward, so that the eye is more rigidly clamped against the pillar.

In the example shown in Fig. 7, the leaf 105 spring 4^b is secured to a plate 21 having a shank 22 projecting upward therefrom and a lip 23 projecting outward. The latter is made with a pair of notches 24 adjoining the shank 22. By means of the plate 21 and the 110

notches 24 the spring is held within the slots 3 of the pillar 2. In the example illustrated, the spring is pivotally secured to the plate 21 by means of a pivot bolt 25, and the end 5 of the leaf spring adjoining the shank 22 is rounded concentrically to the pivot bolt 25. The shank 22 of the plate 21 is formed with a nose 26 projecting into the slot 3 of the pillar 2 when in operative position. By the 10 said nose the spring is prevented from being tilted about its longitudinal axis. Therefore, the nose 26 is particularly adapted for use in springs which are pivotally mounted on their supporting plates, which otherwise are 15 subject to being tilted sidewise, if they are turned out of their radial positions. Evidently a nose of this character may also be provided in the example illustrated in Fig. 3.

20 A further modification of the spring is shown in Fig. 8, in which the spring 4^a is formed, at its rear end, with a shank 5^a similar to that described with reference to Fig. 3, and it is secured to a plate 21^a which is 25 formed with a lip 23^a projecting rearward and having a pair of notches 24^a. To enable a plurality of cans to be placed one above the other, adjustable base-plates or shelves 10 may be provided on the pillar 2, as shown 30 in Figs. 4 and 5. The said shelves are supported on the pillar in the same way as the lid holding springs. For this purpose, the shelf 10 is made integral with an arm 11 having a shank 12 projecting upward therefrom, and a flanged piece 13 secured thereto and projecting with its flange downward. With the shanks 12, the plates are inserted 35 into the slots 3 of the pillar 2 in the same way as the lid holding springs, and they are 40 clamped thereon by being turned into their normal positions, as will readily be understood from the description given with reference to Fig. 2. Preferably, the plates are 45 provided with marginal flanges 14 whereby the cans placed thereon are prevented from sliding off.

50 A further example of an adjustable shelf is shown in Fig. 9. As shown in the said figure, the arm 11 of the shelf is secured to a supporting plate 26^a having a flange 27 projecting downward and a horizontal lip 28 projecting beyond the latter. By means of the lip 28 the plate 26^a can be inserted into and clamped to the slots 3 of the pillar 2. 55 For this purpose, the lip is formed with a pair of notches adjoining the shank 27, and engaged by the wall of the pillar 2 when inserted into the slots 3. The base plate 10 and its arm 11 may be pivotally or rigidly 60 secured to the supporting plate 26^a. In the example illustrated, it is connected thereto by means of a pivot bolt 29, and the end of the arm 11 engaging the plate 26^a is rounded. The shank 27 of the supporting plate 65 26^a is provided with a nose 30 engaging the

slot 3 of the pillar 2 when brought in position, and thereby preventing the plate from tilting. In a similar way, a nose may be provided in case of the adjustable base plate illustrated in Fig. 4.

70 In the example illustrated in Fig. 4, two cans are placed one above the other. But it should be understood, that any suitable number of cans can thus be placed one above the other, according to the height of the pillar and that of the cans. Instead of providing a separate adjustable base plate 10 for each of the cans, a common shelf made of 75 two sections may be provided for all the cans disposed in the elevated position. 80 When thus using a common shelf for all the cans, the cans can be more advantageously distributed, and a greater number of cans be placed on the shelf, than in case of separate shelves for each of the cans. However, cans of different heights can not be arranged on 85 the same base plate.

90 In the example illustrated in Figs. 4 and 5, the shelf 15 consists of two sections, one of which is shown in the figures. Each of the said sections is provided, at its bottom face, with a semi-circular flanged disk 16, embracing one half of the pillar, and at its top face it is provided with a flanged disk 17 having at its free end an upwardly extending section 17^a. By means of the latter, 95 each section is inserted into one of the slots 3. Each of the sections of the shelf bears with its flanged disk 16 against the outer face of the pillar, and with its flanged disk 17 against the inner face of the same, and it is clamped thereto in the same way, as 100 the shelves 10 or the lid holding springs, as soon as it is weighted by the cans placed thereon. Therefore it provides a reliable 105 support for the said cans.

I claim:

1. In a sterilizing apparatus, the combination with a can support and a vertical tubular upright or pillar, having therein a 110 plurality of longitudinally extending slots, and a plurality of resilient arms, each having a section extending through one of said slots and projections extending into contact with opposite faces of the wall in which 115 said slot is formed, each of said arms being adapted to contact with the top of a can placed on the can support.

2. In a sterilizing apparatus, the combination with a can support and a vertical 120 upright or pillar, of a resilient arm, comprising two members, pivotally connected, one of said members engaging the upright or pillar and the other member being adapted to engage the top of a can placed on the 125 can support, the pivoted connection between said members permitting the latter to be turned at any angle to the former to properly engage the can top.

3. In a sterilizing apparatus, the combi- 130

nation with a can support and a vertical tubular upright or pillar, having a longitudinally extending slot formed therein, of a resilient arm including two members pivotally connected together, one of said members extending through said slot in the pillar, and having projections extending into contact with opposite faces of the wall in which said slot is formed, and the other 10 adapted to contact with the top of a can placed on the can support.

4. In a sterilizing apparatus, the combination with a pillar having therein a longitudinal slot, of a can support having clamping means adapted to engage said slot and to secure the support at different parts of the slot, a nose on said can support extending into the slot in the pillar, and a spring 15

adapted to engage the lid of a can placed on said support.

5. In a sterilizing apparatus, the combination with a can support, of a pillar having a longitudinal slot providing inner shoulders, and a spring adapted to engage the lid of a can placed on said support and having clamping means adapted to bear against the inner shoulders and the outer margins provided by the slot in the pillar, and a nose extending into the slot.

In testimony whereof I have signed my name to this specification in the presence of two subscribing witnesses.
